UNITED STATES PATENT OFFICE.

ABRAM L. LOWENSTEIN, OF NEW YORK, N. Y.

DESIGN FOR COTTON PIECE GOODS.

41,279.

Specification for Design.

Patented Mar. 28, 1911.

Application filed December 27, 1910. Serial No. 599,537. Term of patent $3\frac{1}{2}$ years.

To all whom it may concern:

Be it known that I, ABRAM L. LOWENSTEIN, a citizen of the United States, and a resident of the city of New York, county of New York, and State of New York, (whose post-office address is 20 West Houston street, in said city,) have invented a new, original, and ornamental Design for Cotton Piece Goods, of which the following is a specification.

Reference is to be had to the accompanying drawing in which the figure is a plan view of a portion of cotton piece goods illustrating my design.

I claim:

The ornamental design for cotton piece goods as shown.

Signed at the city of New York, county of New York, State of New York, this 23rd day of December, 1910.

ABRAM L. LOWENSTEIN.

Witnesses:

GUSTAVE I. ARONOW,
H. RADZINSKY.

Copies of this design may be obtained for five cents each, by addressing the "Commissioner of Patents, Washington, D. C."
